SWAGING APPARATUS

Fulvio De Fazi, New York, N. Y., assignor of one-half to Carlo De Fazi, Jamaica Plain, Mass.

Application June 4, 1943, Serial No. 489,662

6 Claims. (Cl. 76—4)

This invention is a device or apparatus for impressing indentations, cavities, or matrices of any desired shape, capable of being produced by a swaging operation, into bodies, and more particularly into metal bodies, and especially into metal forming rolls or like cylindrical elements.

The invention had its conception in connection with forming rolls for producing ribs on reinforcing bars used in concrete constructions, and while I disclose herein and specifically describe an embodiment of the invention for the treatment of such rolls, I wish it to be understood that the invention is not limited to this use, as obviously it has many other applications.

Rolls for forming ribs on reinforcing bars, or for producing ornamental or other designs in relief upon elongated metal articles, operate in pairs provided with registering circumferential grooves; and at the line of contact between two such rolls, said grooves produce a through passage having the cross sectional size and shape of the body portion of the bar or article upon which the rolls are intended to operate, and through which such bar or article is fed as the rolls rotate. The ribs, or designs in relief, are formed upon the bars or articles, when the latter are hot, by indentations, incisions, matrices or cavities that are sunk or depressed within the walls of said grooves. Heretofore, such indentations, incisions, matrices or cavities were made by milling or otherwise cutting away the material of the rolls, and such work has been tedious, slow and difficult, and accordingly very expensive, especially where peculiar shapes and arrangements of ribs are desired or more or less intricate designs are required.

The fundamental purpose of my invention is to provide a swaging device or apparatus including a tool or hob by which the indentations or cavities are impressed into the metal of the rolls, thereby greatly expediting and cheapening the work, and at the same time improving the character of the rolls in the region of the indentations by reason of the fact that the metal is compressed, rather than cut away, thereby greatly increasing the density of the molecular structure of the rolls in such regions where hardness is essential to high quality of product as well as to longevity of the rolls.

Another object of my invention is to provide a device or apparatus wherein a roll may be easily and quickly mounted for treatment, and wherein it is properly centered, notwithstanding possible differences in diameter among the rolls to be treated, means being provided for com-

pensating for such differences within a practical range. In this connection it may be explained that the aforesaid differences may represent reasonable tolerances allowed in the machining of the surfaces of the rolls, or they may result from the fact that forming rolls gradually wear and have to be reconditioned by reformation of the grooves, etc.

Another object of the invention is to provide indicating or indexing means for enabling the work, such as a roll, to be properly positioned with respect to the tool or hob, and the indentations or impressions to be properly spaced from one another.

15 A further object is to provide clamping means by which the work may be quickly and conveniently locked in position while being acted upon by the tool or hob, and which may be released with equal facility preparatory to adjusting the work for the next indentation and impression.

A still further object is to provide a very substantial and compact apparatus of the above described character that, according to my present preference, is operated by a hydraulic jack, but 25 which, with slight alteration, as by dismantling the parts that sustain such jack in operative relation to the tool or hob, may be conditioned for placement between the plunger and platen of a hydraulic press for operation thereby.

30 The foregoing objects, with others hereinafter appearing, are attained in the embodiment of the invention illustrated in the accompanying drawings wherein Fig. 1 is a side elevational view of the swaging device or apparatus; Fig. 2 is a left hand end elevation of the same; Fig. 3 is a plan view; Fig. 4 is a transverse section on the line 4—4 of Fig. 1, the superstructure being broken away; Fig. 5 is a perspective view of the swaging tool or hob; Fig. 6 is a similar view of an adjustable stop therefor; Fig. 7 is a central, vertical, longitudinal section through the apparatus; Fig. 8 is a vertical transverse section, substantially on the line 8—8 of Fig. 7, the tool or hob and the hydraulic jack being shown in elevation; Figs. 9

40 and 10 are sections on the respective lines 9—9 and 10—10 of Fig. 7; Fig. 11 is a fragmentary side elevation of a reinforcing bar that is a product of the rolls that are treated by the swaging apparatus as herein illustrated, and Fig. 12 is a 45 cross sectional view of the bar.

I shall now proceed with a more detailed description of the invention by the use of reference characters. 1 designates the body of the apparatus and, according to the present illustration, 50 the same is in the form of a rectangular block

having an axial bore 2 that constitutes the work-receiving cavity. The body is provided with a vertical guideway 3 that opens, at its inner end, into the bore 2, in radial relation thereto, and at its outer end through the top of a boss 4 that rises from the body. The bore 2 converges inwardly from its ends at a very slight angle to its axis, and fitting within the ends of the bore are tapered split bushings 5 and 6 within which is adapted to be supported the forming roll R that is to be treated, said roll representing the work upon which the present apparatus is designed to operate. Engaging the outer ends of the split bushings 5 and 6 are pressure rings 7 and 8, respectively, that are shown as formed with apertured ears 9 through which screws 10 are engaged that are threaded into the ends of the body 1. By drawing up on the screws 10, the pressure rings 7 and 8 will be caused to urge the bushings into the converging ends of the bore 2 thereby to contract the bushings about the roll R and center it within the bore. The adjustment should be such that the roll will be capable of being rotated within the bushings with comparative ease.

Projecting from the ends of roll R are shaft sections or trunnions r , r' , the latter projecting through a split clamping collar 12 incorporated in a standard 13 that is secured to a base 14 which projects from one end of the body 1. Also secured to and rising from the base 14 beyond the end of the shaft section or trunnion r' is a bracket 16 having a lateral extension 17 at its upper end. Threaded through the body portion of the bracket 16 is a screw 18 so arranged that it may be engaged by the end of the shaft section or trunnion r' and thus constitute an adjustable stop for limiting the movement of the roll R in one direction. Fastened, as by set screws 19, to said shaft section or trunnion r' is an indexing disk or indicator 20 having cavities 21 spaced about its periphery that are adapted to receive the end of a plunger 22, shown as a screw that operates within a threaded hole in the extension 17 of the bracket 16.

As previously explained, the present embodiment of the invention is intended for the treatment of rolls employed in the forming of ribs or reinforcing bars used in concrete constructions. Such rolls operate in pairs and each is provided with a circumferential groove that registers with the groove of the other roll to form a through passage at the line of contact between the rolls having a cross-sectional size and shape of the finished bar. The circumferential groove of the present roll R is designated r^2 and the roll is adapted to be positioned within the bore 2 with said groove in radial alignment with the guideway 3. When the work is properly set up within the apparatus, it is held against axial movement in one direction by the engagement of the shaft section or trunnion r' with the screw 18, as above explained, and in the opposite direction by the engagement of the hub of the indexing disk 20 with the collar 12.

A tool or hob 25 slidably fits the guideway 3, and at its inner end is shaped to provide a tooth 26 for making indentations r^3 in the wall of the groove r^2 . Said tool or hob, as herein illustrated, forms indentations that are disposed at right angles to the plane of the groove. Obviously, the angle may be changed by employing a hob having its tooth so inclined to the axis of the bore 2 as to produce the desired effect. At its outer end the tool or hob terminates in an extension 27

that carries an adjustable stop 28. This stop may consist of a split nut that is threadedly engaged with said extension and is adapted to be firmly clamped to the extension 27 in any position of adjustment by means of a screw 29 so arranged that the stop may be contracted about the extension by turning the screw in the appropriate direction.

Rising from the body 1 on opposite sides of the boss 4 are columns 30. As shown, their lower ends are reduced and threaded and are screwed into threaded sockets in the body. A relatively heavy cross beam 32 is detachably connected to the upper ends of the columns 30 as by being notched adjacent its ends and engaged within circumferential grooves of the columns. As will appear from Fig. 3, one of the notches, 33, opens through the end of the cross beam, while the other, 34, opens through a side thereof. A hydraulic jack 35 is sustained by the cross beam 32 with its plunger 36 in axial alignment with the extension 27 of the hob 25. The operating handle of the jack is designated 37.

To condition the apparatus for the reception and treatment of a roll, the screws 10 are retracted to allow the split bushings 5 and 6 to expand; the clamp 12 is relaxed; the assembly of cross beam 32 and jack 35 is swung out of the way, or detached from the columns 30 and laid aside, and the hob 25 is lifted or withdrawn from the guideway 3. The roll R is then inserted into the cylindrical bores of the bushings 5 and 6 (from a position to the right of the apparatus, as the same is viewed in Figs. 1, 3 and 7) until the end of the shaft section or trunnion r' engages the stop provided by the screw 18, the latter being adjusted so as to locate the groove r^2 of the roll in the plane of the guideway 3. As said shaft section or trunnion is projected beyond the clamp 12, the indexing disk 20 is applied thereto and, with the inner end of its hub engaged with the clamp 12, the set screws 19 are tightened to firmly secure said disk to the trunnion. Now, by turning the screws 10 in the direction to press the bushings 5 and 6 further into the tapered ends of the bore 2, said bushings are contracted to properly center the roll R within the bore. The roll is next rotatively adjusted so that the plunger 22 may be projected into one of the recesses 21 of the disk 20 after which the clamp 12 is tightly contracted about the shaft section or trunnion r' to hold the roll firmly in place. The hob is then dropped into the guideway 3 until its tooth 26 strikes the work, whereupon the stop 28 is adjusted along the extension 27 to leave a space between the lower end of the stop and the top surface of the boss 4 equal to the desired depth of the indentations that are to be made in the wall of the groove r^2 (this adjustment determining the radial dimension of the ribs b of the reinforcing bar B, shown in Figs. 11 and 12). When the stop 28 is so adjusted, it is firmly locked to the extension by means of the screw 29.

The assembly of the cross beam 32 and hydraulic jack 35 is then returned to its former position, after which the jack may be operated by means of its handle 37 to force the hob 25 downwardly until the stop 28 engages the boss 4. This action produces an indentation r^3 in the wall of the groove r^2 . The hydraulic jack is then relaxed and the hob lifted so as to remove its tooth 26 from the indentation; the clamp 12 is next loosened and the plunger 22 retracted, so as to free the roll R for rotation, and the latter is then turned until the next recess is brought into align-

ment with the plunger 22 when the plunger is projected into said recess to properly position the roll for the next indentation r^3 . When so positioned, the clamp 12 is reset to firmly hold the roll. This procedure is continued until indentations are equally spaced apart throughout the entire circumference of the roll, when the set screws 19 are loosened, the clamp 12 relaxed, the screws 10 retracted sufficiently to permit some expansion of the bushings 5 and 6, the cross bar and jack assembly removed, the hob lifted, and the roll withdrawn from the apparatus.

If desired, and especially where the nature of the work requires a heavier pressure than can be obtained from a manually operated hydraulic jack, the cross beam and jack assembly and the columns 30 may be removed and the apparatus placed on the platen or table of a hydraulic press in such a position that the plunger of the press will engage the extension 27 of the hob 25 when the press is operated.

Having thus described my invention, what I claim is:

1. In swaging apparatus for producing indentations in the walls of the circumferential grooves of forming rolls, a body having a work receiving cavity somewhat greater in diameter than the roll and wherein the roll is adapted to be positioned, the cavity opening through the end of the body, a split bushing fitting about the roll and within the cavity for centering the roll in the cavity, the body being provided with a guideway that opens into said cavity, a hob guided therein for operation upon the roll, the roll being positioned with its groove in radial alignment with the hob, and means for imposing pressure upon the hob.

2. In swaging apparatus for producing indentations in the walls of the circumferential grooves of forming rolls, a body having a work receiving cavity somewhat greater in diameter than the roll and wherein the roll is adapted to be positioned, the cavity opening through the end of the body and being tapered inwardly from said end, a split tapered bushing fitting about the roll and within the cavity for centering the roll in the cavity, means for forcing the bushing into the cavity, the body being provided with a guideway that opens into said cavity, a hob guided therein for operation upon the roll, the roll being positioned with its groove in radial alignment with the hob, and means for imposing pressure upon the hob.

3. In swaging apparatus for producing indentations in the walls of the circumferential grooves of forming rolls, a body having a work receiving cavity that opens through the end of the body, said cavity being circular in cross section and somewhat larger in diameter than the roll and being tapered inwardly from said end, a split tapered bushing fitting about the roll and into said cavity, a pressure plate engaged against the outer end of the bushing, screw means for urging said plate toward the body thereby to contract the bushing about the roll, the body being provided

with a guideway opening into the work receiving cavity, a hob guided therein for operation upon the roll and in radial alignment with which the groove of the roll is adapted to be positioned, and means for imposing pressure upon the hob.

4. In swaging apparatus for producing indentations in the walls of the circumferential grooves of forming rolls, a body having a work receiving cavity consisting of a bore extending through the body, split bushings engaged within the ends of the cavity and having internal cylindrical surfaces, the body being provided with a guideway opening into the cavity between the inner ends of the bushings, a hob guided in said guideway, the roll being adapted to be supported within the bushings with its groove in radial alignment with the hob, the roll being adapted to be rotated within the bushings, means for securing the roll in different positions in which it may be rotated for operation thereon by the hob, and means for imposing pressure upon the hob.

5. In swaging apparatus for producing indentations in the walls of the circumferential grooves of forming rolls, a body having a work receiving cavity consisting of a bore extending through the body, said bore tapering inwardly from both ends, split tapered bushings engaged within the ends of the cavity and having internal cylindrical surfaces, the body being provided with a guideway opening into the cavity between the inner ends of the bushings, a hob slidable in said guideway, the roll being adapted to be supported within the bushings with its groove in radial alignment with the hob, pressure plates applied to the outer ends of the bushings, screw means for forcing the pressure plates toward the body, the roll being adapted to be rotated within the bushings, means for securing the roll in different positions to which it may be rotated for operation thereon by the hob, and means for imposing pressure upon the hob.

6. In swaging apparatus for producing indentations in the walls of the circumferential grooves of forming rolls, said rolls being provided with axial shaft sections, a body having a through bore for the reception of a roll and of a diameter somewhat larger than the roll, said bore being tapered inwardly from both ends, tapered bushings fitting about the roll and within the ends of the bore, means engaged with the outer ends of the bushings for forcing them into the bore, the body being provided with a guideway opening into said bore between the inner ends of said bushings, a hob slidable within the guideway, adjustable stop means for positioning the roll with its groove in radial alignment with the hob, a base extending from the side of the body through which one end of the aforesaid bore opens, clamping means sustained by said base and encircling a shaft section of the roll for securing the roll in different orientated positions, an indexing disk secured to the shaft section, and stop means supported by the base for cooperation therewith.

FULVIO DE FAZI.
